HAND TOOL

John V. Larson, Chicago, Ill.

Application April 6, 1942, Serial No. 437,809

3 Claims. (Cl. 81—127)

This invention relates to hand tools and more particularly to their method of manufacture, although certain features thereof may be employed with equal advantages for other purposes.

It contemplates more especially the provision of hand tools of the wrench type comprising the subject matter of United States Letters Patent 1,602,620 and 1,830,033 which have been simplified in their construction to increase the capacity and to substantially reduce the manufacturing costs thereof by resorting to improved methods of manufacture and assembly.

One object of the present invention is to simplify the construction and improve the operation of devices of the general character mentioned.

Another object is to provide a novel method of structurally forming hand tools into complementary parts that can be advantageously assembled to increase the capacity and minimize the production expense thereof.

Still another object is to provide an improved method of manufacture for hand tools that may embody cast parts capable of simple assembly without entailing any appreciable machine finishing operations.

A further object is to provide a hand tool of the pivoted handle type wherein the connection of relatively movable parts is through an integral handle pivot that increases rather than detracts from the operating capacity thereof.

A still further object is to provide a hand wrench in which the operating handle is pivotally connected to a sectional stationary jaw through medium of an integral handle pivot.

Still a further object is to provide a wrench having a sectional jaw of a rigid assembled construction to eliminate appreciable machine finishing operations thereon.

Other objects and advantages will appear from the following description of an illustrated embodiment of the present invention.

In the drawing:

Figure 1 is a top plan view of a hand tool embodying features of the present invention.

Figure 2 is a fragmentary plan view of the wrench handle gear-end portion of the handle operating member.

Figure 3 is a fragmentary front view edge in elevation of the gear-end of the handle member 50 shown in Figure 2.

Figure 4 is a fragmentary perspective view of a stationary jaw section shown in Figure 1, part thereof being broken away to illustrate the cross-sectional shape thereof.

Figure 5 is a sectional view in elevation taken substantially along line V—V of Figure 1.

Figure 6 is a perspective view of a spring confining disc comprising a part of the wrench assembly illustrated in Figure 1.

Figure 7 is a plan view of a special spring used in conjunction with the disc shown in Figure 6.

Figure 8 is a perspective view of the movable jaw that is complementary to the stationary jaw section shown in Figure 4.

Figure 9 is a fragmentary bottom plan view of the tool shown in Figure 1.

Figure 10 is a fragmentary edge view in elevation of the wrench head shown in Figure 9.

Figure 11 is a perspective view of the stationary jaw plate section that is complementary to and capable of a rigid assembly with the jaw section shown in Figure 4.

Figure 12 is a plan view of the stationary and movable jaw having the spiral spring assembled therewith, part thereof being broken away to clarify the showing.

The structure selected for illustration is not intended to serve as a limitation upon the scope or teachings of the invention, but is merely illustrative thereof. There may be considerable variations and adaptations of all or part of the teachings depending upon the dictates of commercial practice.

The illustrated embodiment comprises an elongated wrench handle 10 that is forged or preferably cast from an alloy steel composition to present a somewhat tapered manipulating shank 35 that terminates in the progressive jaw operating gear 11 that effects the relative displacement of the jaws through the medium of a pivot pin 12 which, in this instance, comprises oppositely projecting trunnions 13—14 (Figure 3) formed integrally with the handle 10 proximate to progressive gear-end 11 thereof. The integral pivot 12 will thus eliminate any weakening of the handle member 10 in the region of the gear-end 11 which is ordinarily the weakest and most sustains the greatest operating load. It has heretofore been thought necessary to provide a bore through the gear-end region 11 to accommodate an independent pin as is clearly shown in United States Letters Patent 1,602,620 and 1,830,033. This presented an extremely weak region that had to sustain a large part of the load. With the teachings of the present invention, the integral trunnions 13—14 constitute the pivot pin 12 which strengthens rather than weakens the gear-end region 11 of the handle 10.

A rigid jaw 15 is cast or otherwise shaped from any suitable material to provide a depending body plate 16 (Figure 4) having a groove 17 provided transversely therethrough to serve as a guide for the movable jaw as will appear more fully hereinafter. Above groove 17 there is provided a shoulder 18 proximate to the jaw 15 to serve as a base for an integral stud 19 that projects therefrom. The lower end of the jaw plate 16 is provided with a longitudinally extending nib 20 serving as a finger manipulating projection as will appear more fully hereinafter.

A companion jaw plate 21 (Figure 11) is shaped to serve as a complement of the jaw plate 16 and its shoulder 18 for assembly therewith. To this end, the confronting jaw plates 16-21 are provided on the aligned apertures or bores 22-23 which are adapted to receive the trunnions 13-14 while another aperture in the body plate 21 is positioned and sized to receive the stud 19 to enable their rigid assembled association by spinning or swaging the projecting extremities of the trunnions 13-14 and stud 19 after all of the parts have been assembled therebetween. It should be noted that the body plate 21 also is provided with a longitudinally extending nib 26 that confronts the nib 20 on the body plate 16 to afford finger manipulation of the jaw 15 for presetting and removal relative to a nut or other instrumentality that is to be turned therewith.

A movable jaw 27 is shaped to correspond with and to oppositely confront the relatively stationary jaw 15. To this end, the movable jaw 27 has a transverse shank 28 inwardly offset from the jaw 27 which is appreciably thicker than the guide shank 28 thereof. This presents oppositely extending shoulders 29 at the juncture of the jaw 27 with the guide shank 28 to ride along the spaced top edges 30-31 of the jaw plates 16 and 21, respectively. As shown, the jaw shank 28 is provided with a plurality of rack teeth 32, in this instance three, that are complementary to and mesh with the progressive gear attached on the handle 10 when the jaws 15-27 are in operative assembled relation to effect their relative sliding displacement responsive to pivoting the handle 10.

In order to guide the movable jaw 27 relative to the stationary jaw 15, the jaw shank 28 is provided with an elongated ridge or shoulder 33 extending for the length thereof to serve as a complement to the groove 17 in the jaw plate 16. With the movable jaw 27 in movable operative relation with the stationary jaw 15 the plate 21 is disposed thereover with the handle 10 and its progressive gear-end 11 in meshing engagement with the rack 32 of the jaw shank 28. Thereupon the projecting end of the stud 19 is spun or swaged to overlap the body plate 21 to maintain the parts in assembled relation. Corresponding spinning or swaging of the projecting portion of the pivot trunnion 14 to securely maintain the cooperating jaws 15-27 and their cover plate 16-21 in assembled association. Thereupon, a spiral spring 34 having a radially extending inward extremity 35 and a hooked outer extremity 36 is enveloped around the pivot trunnion 13 for lodgement in a correspondingly shaped recess 37 formed in the exterior surface of the jaw plate 16 in concentric relation with the aperture or bore 22 therethrough.

The radial inward extremity 35 of the spring 34 is projected through a somewhat larger aperture 38 provided radially in the pivot trunnion 13 (Figure 3). The hooked extremity 36 of the

spiral spring 34 engages a lateral projection 39 stamped or otherwise shaped from the material of a disc 40 that is sized to overlap the concentric recess 37 which receives the spring 34. To this end, the disc 40 is provided with an axial aperture 41 that receives the trunnion 13 therethrough for assembled association of the disc 40 over the spring 34 and its recess 37 for contact with the external surface of the jaw plate 16 (Figure 5). With the disc 40 positioned to impart the desired tension in the spring 34, the lateral projection 39 not only serves to engage the hooked spring extremity 36, but also is then lodged in an aperture 42 provided in the jaw plate 16 within the limits of the spring recess 37 (Figure 4). This serves to retain the disc 40 in the desired position with the tension in the spring 34 maintained so that the jaws 15-27 will be urged to normally approach each other to their maximum limit without any nut or other member disposed therebetween.

With the arrangement of the parts above described, the projecting end of the trunnion 13 is then spun or swaged to overlap the disc 40 and thus maintain the parts in rigid assembly with the cover plates 16-21 in rigid connection through the medium of the spun or swaged trunnions 13-14 and stud 19. This construction and method of assembly eliminates the necessity of forged parts that require expensive dies and reduces the machine finishing operations to a minimum. Heretofore the jaw 15 with its confronting cover plates 15-21 were forged or otherwise shaped from a single piece of material so that a very difficult and comparatively expensive milling operation was necessary to provide the grooves therethrough for receiving the movable jaw 27 and its transverse guide shank 28. Additionally, weaknesses developed in the region of the gear-end 11 of the handle 10 owing to the weakened construction that was heretofore occasioned by the pivot receiving aperture heretofore provided therethrough.

It will be observed that with the attendant grasping the handle 10, the forefinger or thumb is available to engage the longitudinally projecting nibs 20-26 on the cover plates 16-21 to cause the jaws 15-27 to recede from each other for convenient application to a nut or other fastening expedient or to effect the release thereof from engagement after the turning effort on the handle 10 has been withdrawn. A novel construction and method of assembly has been provided that improves the capacity and substantially decreases the expense of production.

While I have illustrated and described a preferred embodiment of this invention, it must be understood that the invention is capable of considerable variation and modification without departing from the spirit of the invention. I, therefore, do not wish to be limited to the precise details of construction set forth, but desire to avail myself of such variations and modifications as come within the scope of the appended claims.

I claim:

1. A hand tool comprising a handle member, oppositely projecting jaw pivots extending from one end of said handle member, confronting jaw plates mounted on said pivots to swing relative to said handle member, complementary means between said jaw plates and said handle member for maintaining said confronting jaw plates in rigid spaced relation, a fixed jaw on said plates, a movable jaw opposed to said fixed jaw and slidably disposed between said confronting jaw plates,

inter-engaging gear teeth on said handle member and movable jaw to effect relative jaw displacement responsive to imparting movement to said handle member relative to said jaws, spring means enveloping one of said jaw pivots, an apertured disc cooperating with said last named pivot to encase said spring means against an adjacent jaw plate, and a depending nib on said disc to anchor one end of said spring means, the other end of said spring means being anchored to said last named pivot, there being an aperture in one of said jaw plates to receive said disc nib to anchor said disc and engaging spring extremity against displacement and to maintain a pre-determined tension in said spring means.

2. A hand tool comprising a handle member, oppositely projecting jaw pivots formed integral with one end of said handle member, confronting jaw plates mounted on said pivots to swing relative to said handle member, a stud cast integral with one of said jaw plates to project through the other of said jaw plates to effect their connection by being peened thereover, said stud being spaced from said handle pivots to cooperate therewith in maintaining said jaw plates in assembled connection with said handle, complementary means between said jaw plates and said handle member for maintaining said confronting jaw plates in rigid spaced relation, a fixed jaw on said plates, a movable jaw opposed to said fixed jaw and slidably disposed between said confronting jaw plates, said handle pivots being peened to overlap said jaw plates to establish a pivotal retaining connection therebetween, inter-engaging gear teeth on said handle member and movable

35

jaw to effect relative jaw displacement responsive to imparting movement to said handle member relative to said jaws, and spring means interposed between one of said jaw plates and adjacent handle pivot to normally urge said jaws toward each other.

3. A hand tool comprising a handle member, oppositely projecting jaw pivots formed integral with one end of said handle member, confronting jaw plates mounted on said pivots to swing relative to said handle member, complementary means between said jaw plates and said handle member for maintaining said confronting jaw plates in rigid spaced relation, a fixed jaw on said plates, a movable jaw opposed to said fixed jaw and slidably disposed between said confronting jaw plates, said handle pivots being peened to overlap said jaw plates to establish a pivotal retaining connection therebetween, inter-engaging gear teeth on said handle member and movable jaw to effect relative jaw displacement responsive to imparting movement to said handle member relative to said jaws, spring means enveloping one of said jaw pivots, an apertured disc cooperating with said last named pivot to conceal said spring means, and a depending nib on said disc to anchor one end of said spring means, the other end of said spring means being anchored to said last named pivot, there being an aperture in one of said jaw plates to receive said disc nib to anchor said disc and engaging spring extremity against displacement and to apply a pre-determined tension to said spring means.

JOHN V. LARSON.
